UNITED STATES PATENT OFFICE.

EMERY E. TREMAIN, OF STOCKTON, CALIFORNIA.

COMBINATION-TRUCK.

1,319,312.

Specification of Letters Patent.

Patented Oct. 21, 1919.

Application filed August 17, 1918. Serial No. 250,409.

To all whom it may concern:

Be it known that I, EMERY E. TREMAIN, a citizen of the United States, residing at Stockton, in the county of San Joaquin, 5 State of California, have invented certain new and useful Improvements in Combination-Trucks; and I do declare the following to be a full, clear, and exact description of the same, reference being had to the 10 accompanying drawings, and to the characters of reference marked thereon, which form a part of this application.

This invention relates to improvements in truck bodies, and particularly to that 15 type attached to motor trucks known as dumping bodies, the principal object of the invention being to produce such a body in which the sides may be spread out level with the floor for the purpose of transporting wide and bulky articles such as furniture, heavy machinery, etc., which feature 20 will widen the scope of usefulness of such dumping body trucks, the use of which is at present confined to the hauling of such 25 materials as gravel, rock, loose cement, and the like.

A further object is the combination with 30 the drop-sides of an end board which may swing out when the body is raised to dump and which is removable when the sides are dropped, thus leaving a flat platform unobstructed by any vertical members which would limit the size and shape of any article 35 placed thereon.

35 A third object of the invention is to produce such a body as will be inexpensive of construction and simple of operation and which will be extremely efficient for the purposes for which it is designed.

40 These objects, I accomplish by means of such structure and relative arrangement of parts as will fully appear by a perusal of the following specification and claims.

On the drawings, similar characters of 45 reference indicate corresponding parts in the several views.

Figure 1 is a side elevation of my improved body, shown in dumping position on the frame of a motor truck.

50 Fig. 2 is a cross section taken relatively on a line 2—2 of Fig. 1.

Fig. 3 is an enlarged fragmentary view showing an end board catch and release.

55 Fig. 4 is a fragmentary top view showing the connection between the front end and side boards.

Referring now more particularly to the characters of reference on the drawings, the numeral 1 designates the main frame of the truck, to the rear end of which is 60 hinged, as at 2, the body 3 of the truck. The frame of the body is built up in the customary manner of longitudinal beams or stringers 4 to which the end hinges are secured, cross beams 5 extending over the 65 beams 4, and suitable flooring 6 laid lengthwise on the beams 5, the flooring extending rearward beyond the hinges 2 for a certain distance to prevent the material being dumped from falling on the truck frame. 70

Mounted to the floor 6 by means of a plurality of hinges 7 are side boards 8 whose lower edges are normally adjacent the top of the floor, the hinge pins being one continuous rod 9 running lengthwise of the 75 body on each side. Secured to the side boards at spaced intervals are rigid vertical supports 10, these supports extending downward below the level of the floor and side boards, and being adapted to bear on 80 the underside of the floor when the sides are lowered to retain the sides level with the floor.

These supporting members are bent outwardly as at 11, in order to pass around 85 the hinge-pin 9 without bearing against the same.

They are also preferably constructed of channel iron or similar shapes, in which great strength and rigidity is combined with 90 lightness.

The front end of the body is connected with the usual hydraulic lift 12 whereby the body is raised for dumping.

The forward ends of the side boards 8 project over the ends of the front end board 14, which is rigidly mounted to the body 3. Such forward ends are provided with cleats 8^a on either side of the board 14 and straddle the same when the side boards are in 95 vertical position. Straps 15 are secured to the side boards on the outside thereof in line with the rearmost of the cleats 8^a, and a rod 16 passes through the straps 15 and the said rearmost cleats, which rod is provided with 100 hand screws 17.

At the rear end of the side boards are secured straps 18 projecting above the top of the side boards. Straps 18^a are secured to the rear end board 19 projecting over the 110 top thereof, such projected ends being bent to form eyes in line with the straps 18.

A rod 20 passes through straps 18 and 18^a with hand screws 21 thereon, such end board being held solely by the rod 20 and adapted to swing on such rod as a pivotal point. The 5 end board 19 is held normally against the side boards 8 by means of catches 22 on the outer ends of straps 22^a mounted under the floor on one of the cross beams 5, such straps being of spring steel and normally pressing 10 upward to hold the catches in engagement with the outside of the end board 19.

A rod 23 is turnably mounted to the floor above the straps 22^a and has lugs 24 thereon adapted to bear against the straps. This rod 15 has an arm 25 downwardly depending therefrom, which arm has a connected rod 26 pivotally secured thereto running to the forward end of the body and connected at that point to an operating lever 27 mounted on 20 the body 3. Thus when the lever is pulled, the lugs 24 are pulled down against the straps 22 which pressure pulls the catches out of engagement with the end 19 and allows the same free movement outwardly.

25 In the operation of the device, supposing it is desired to use the body as a dumping body only, the sides remain in their vertical position being held there by the hinges 7 at the bottom and the rods 16 and 20 with the 30 screws 17 and 21 at the top. The rear end board is then free to open out as the body is raised by the operation of the lever mechanism hereinbefore described.

Should it be desired, however, to use the 35 body as a flat platform, the screws 17 and 21 are removed from their respective rods, the sides are then lowered to a horizontal position till they rest on the supports 10. This, of course, frees the rear end board 19 from 40 any connection with the body and the same may be stored or carried on the truck in any suitable place until such time as it is desired to reassemble the sides of the truck body.

From the foregoing description it will be 45 readily seen that I have produced such a device as substantially fulfills the object of the invention as set forth herein.

Copies of this patent may be obtained for five cents each, by addressing the "Commissioner of Patents, Washington, D. C."

While this specification sets forth in detail the present and preferred construction of the device, still in practice such deviations 50 from such detail may be resorted to as do not form a departure from the spirit of the invention, as defined by the appended claims.

Having thus described my invention, what I claim as new and useful and desire to secure by Letters Patent is:

1. In combination with a dumping truck body having a front end board rigidly mounted to the flooring and side boards hinged to the flooring and adapted to be 60 lowered to the level of the floor and retained in that position, demountable means common to both side boards at the upper front and rear ends thereof whereby the same may be held in a vertical position, and an end gate 65 hinged along its upper edge to the rear one of such side board holding means, whereby when the body is raised to dump the truck the end gate will swing automatically on its hinges, and may be removed with the side 70 board holding means when desired to lower the sides to form a platform.

2. In combination with a dumping truck body having a front end board rigidly mounted to the flooring, and side boards 75 hinged to the flooring and adapted to be lowered to the level of the floor and retained in that position, demountable rods common to both side boards at the upper front and rear ends thereof whereby the same may be 80 held in a vertical position and an end gate hung along its upper edge on the rear one of said rods, whereby when the body is raised to dump the truck, the end gate will automatically swing on the rod, and may be 85 removed with the holding rod when desired to lower the sides to form a platform.

In testimony whereof I affix my signature in presence of two witnesses.

EMERY E. TREMAIN.
